UNITED STATES PATENT OFFICE.

JOHN E. HERRIOTT, OF KANSAS CITY, KANSAS, ASSIGNOR OF ONE-HALF TO
ALEXANDER G. LAUTHERS, OF KANSAS CITY, KANSAS.

COFFEE-ROASTER.

SPECIFICATION forming part of Letters Patent No. 757,743, dated April 19, 1904.

Application filed October 22, 1903. Serial No. 178,095. (No model.)

To all whom it may concern:

Be it known that I, JOHN E. HERRIOTT, a citizen of the United States, residing at Kansas City, in the county of Wyandotte and State of Kansas, have invented new and useful Improvements in Coffee-Roasters, of which the following is a specification.

My invention relates to a combined portable furnace and coffee-roaster; and the object of 10 producing a coffee-roaster of the kind is that it can be moved from place to place without having to take it to pieces for that purpose.

Another object that I accomplish by such a coffee-roaster is that the coffee can be roasted 15 and at the same time the oil in the grains can be retained therein and not destroyed, as is the case with most of the coffee-roasters at the present time. I accomplish this in the peculiar manner in which I construct the cylinder that 20 retains the coffee while it is being roasted by first making a suitable cylinder of heavy sheet metal, galvanized iron being preferable. I then place on the inside of the cylinder a layer of fire-clay, and on the inside of the fire-clay I 25 place a heavy layer of soapstone. The heads of the cylinder are constructed in the same manner.

Referring now to the accompanying drawings, Figure 1 is a longitudinal sectional view 30 of my invention, disclosing the manner in which the furnace is constructed and the position of the roasting-cylinder in the furnace. Fig. 2 is a cross-sectional view taken on line A A of Fig. 1, disclosing more clearly the manner in which the roasting-cylinder is 35 constructed. Fig. 3 is a vertical section taken on line B B of Fig. 1 between the inside of the rear end of the furnace and the outside head of the rear end of the roasting-cylinder, disclosing 40 closing perforations through the cylinder-head and perforations through an inner wall of the furnace, which admits of smoke from the inside of the roasting-cylinder to escape therefrom and pass outward up the flue of the cylinder. Fig. 4 is the rear end of the furnace. Fig. 5 is a cross-sectional view taken 45 on line C C of Fig. 1. Fig. 6 is a broken longitudinal section of a removable piece of the roasting-cylinder adapted to be taken out

from the top of the furnace when the cylinder 50 is to be filled with coffee and also to be removed to get the coffee from the cylinder after it is roasted. Fig. 7 is a cross-section taken on line D D of Fig. 6.

With the above explanation I will now 55 further proceed to describe my invention by referring to corresponding numerals on the drawings and specification, in which—

1 is a vertical sectional view of the furnace, which is rectangular in plan, having an extended portion 2, 3 being the top. Through 60 the top and central thereof is a rectangular opening 4. The object of the projecting front end 2 is to provide for grates 5 and an ash-pan 6. The fire-space is provided with a door 65 7. At the rear of the fire-space is a box 8. The object of this box is to receive the coffee after it is browned. Immediately over the fire-space is a heat-reflector 9. The object of this deflector is to carry the heat more directly 70 under the roasting-cylinder, which will be fully described farther on. Over the deflector and at an angle of about forty-five degrees is a drooping shed portion 10, forming the front and cover of the furnace over the fire-space. 75 This shed portion 10 further forms a supporting-truss which will prevent sagging, which would otherwise occur from the weight of the roasting-cylinder.

Vertically secured to the inner edge of the 80 deflector and at the junction of the shed 10 is rigidly secured a journal-seat 11, which supports the front end of the shaft 12, passing through the cylinder.

At the rear end of the furnace I have provided 85 a piece of sheet metal 13 of equal dimensions to the size of the furnace above the box that receives the parched coffee. This is rigidly secured to the inside of the furnace, as indicated at Fig. 3, and is provided with a 90 round opening 14 of equal dimensions to the diameter of the roasting-cylinder.

In the rear end of the furnace I have provided a removable circular end 15, which is secured 95 to the furnace by bolts 16. On the inside of this removable end is a reinforced portion 17, which forms the journal-bearing to the outer end of said shaft 12.

The roasting-cylinder 18 is horizontally suspended on the shaft 12 on the inside of the furnace, as shown, and is adapted to be rotated by means of a crank 19 or may be rotated by steam or gasolene power by placing a pulley on the outer end of shaft 12 instead of crank 19.

I have constructed my roasting-cylinder, first, by providing an outer shell 20, of sheet metal, and on the inside of this metallic shell is a layer of fire-clay 21. Still on the inside of the fire-clay is another layer, 22, constructed of soapstone, and in order that the soapstone layer may be firmly secured against the layer of fire-clay I make it in the form of barrel-staves, as shown in Fig. 2.

The staves are designated 23, four of them projecting outward, as shown, about twice the thickness of the others. The object of these 20 projecting staves is to more effectually agitate and stir the coffee as the cylinder revolves. I have constructed this cylinder so that the portion of one of the staves (designated 24) can be removed and replaced at will. The object 25 of this removable section is to form an opening in the cylinder to admit the unbrown coffee to enter the cylinder and the browned coffee to be taken from the cylinder after the browning process is performed. I have provided the heads 25 constructed of the same 30 material and in the same manner. The head in the rear end of the cylinder is provided with perforations 26. The object of these perforations is to let the smoke occasioned by the browning process of the coffee to escape from the cylinder. It passes out of the cylinder through these perforations between the inner head 13 of the furnace and the outer head 15, then upward in the direction of the arrows 35 40 through perforation 27 to the smoke-stack, as indicated.

In order to hold the rear head of the cylinder secure, I have provided iron rods 28. These rods are secured to the projecting ends 45 of the metallic outer portion of the cylinder, as shown. The removable portion 24 of one of the stave-sections of the cylinder is in the form of a dovetailed block; but its sides and the two ends fit snugly when replaced in the 50 cylinder. At Figs. 6 and 7 I have shown sections enlarged, so that this removable piece may be readily understood. To secure this section to the cylinder, I have provided a T-shaped bolt 29, which is pivotally secured 55 through the removable section 24, the outer end of which is provided with an eye 30. When the removable section 24 is to be removed, the bolt 29 is turned in the opposite direction from that as shown in Figs. 6 and 7. 60 At the rear end of the furnace I have provided a door 31, which closes the opening

through which the box 8 is inserted to catch the browned coffee when emptying from the browning-cylinder. I have further provided a longitudinal rectangular opening in 65 the top of the furnace correspondingly of the size of the opening in the browning-cylinder. I have further provided a hopper 32, which engages said opening and extends downwardly to or near the outward surface of the roasting-cylinder. When the cylinder is to be filled with the green coffee, it is turned around until the removable section therein stands fair with the hopper 32 and the opening in the top of the furnace. The removable section is then 70 removed and the hopper is inserted. The coffee is then emptied into the cylinder through the hopper, the removable section replaced, and the T-shaped bolt 29 turned as indicated in Fig. 7, when it is made secure therein. 75 80

To close the opening in the top of the furnace when the hopper 32 is removed, I have provided a trap-door 33, which will fit snugly over the opening and prevent combustion from passing out through the opening. 85

Having now fully described my invention, what I claim as new, and desire to secure by Letters Patent of the United States, is—

1. In a coffee-roaster of the character described, the combination of a furnace, a rotating cylinder mounted in the furnace, constructed of metal, fire-clay and soapstone, a removable section in the periphery of the cylinder, an elongated opening in the top of the furnace, a hopper adapted to engage said opening and correspondingly engage over the removable section in the cylinder, a fire-bed in the lower front end of the furnace and a combustion-discharge pipe on the top rear end of the furnace adapted to cause the heat to envelop the cylinder on its exit from the fire-bed to the combustion-pipe, substantially as described. 90 95

2. In a coffee-roaster of the character described, the combination of a furnace, a rotating roasting-cylinder composed of soapstone, fire-clay and metal mounted in the furnace, an inward sheet-metal head 13 supported in the rear end of the furnace, a circular opening in said head adapted to admit the rear end of the roasting-cylinder to loosely engage, an outer removable head 15 at the rear end of the furnace forming a coffee-smoke-chamber between the outer and the inner heads, substantially as described. 100 105 110 115

In testimony whereof I affix my signature in the presence of two witnesses.

JOHN E. HERRIOTT.
